LOUDSPEAKER ARRANGEMENT

Heinrich Benecke and Leo Bialk, Berlin, Germany, assignors to Telefunken Gesellschaft für Drahtlose Telegraphie m. b. H., Berlin, Germany, a corporation of Germany

Application November 16, 1938, Serial No. 240,650
In Germany November 10, 1937

1 Claim. (Cl. 181—31)

For outdoor entertainment and public address systems, and also for enclosed rooms or spaces, it is often desirable to have the loudspeaker mounted in some concealed place. According to 5 the invention, arrangements are made so that the sound issues from underneath the floor or ground. The loudspeakers therefore are mounted below the floor or the ground. In order that the range or area supplied with sound may be 10 larger in reference to the vertical axis, and in order that, in reference to the horizontal axis, the higher pitches may be reproduced with better quality, the axis of the loudspeaker to the horizontal line is preferably inclined at an acute 15 angle. This plan moreover offers the advantage that the loudspeakers will not be impaired in their operation by rain and splashing water and are protected against the entry of foreign bodies. In the vicinity of the loudspeaker the bottom 20 (ground) plank must be shut and protrude somewhat above the loudspeaker in order to prevent the entrance of dirt. At a little greater distance from the loudspeaker, a grating is provided, built so ruggedly that it will stand the weight of a 25 person standing thereon. Of course, this grating must also be so proportioned that the acoustic properties of the loudspeaker will not be influenced at all or only slightly. It will be understood that drain ducts to carry away rain 30 and other water will have to be provided.

In the appended drawing Figs. 1, 2 and 3 show exemplified embodiments of the present invention. Fitted into the ground is a box 1 in which is accommodated the loudspeaker 2. The loudspeaker divides the box into two parts, care 35 having to be taken so that the sound waves issuing from the front of the diaphragm will not have a chance to communicate with the wave given off from the posterior face thereof. In order to avoid space resonances, it is recom- 40 mendable to drape the space posteriorly of the diaphragm, as known in the art, with felt 3 or by packing it with cotton or the like. For carrying off rain water, a drain hole 4 is provided. The horn-like construction as shown offers the 45 advantage that the use of the device is made essentially independent of the acoustic properties of the posterior space, provided it is not of unduly limited dimensions. Owing to the fact that the loudspeaker is mounted in the enclosure a little distance away from the grating 5 part 6 of the top cover plate will protect the loud- 50 speaker from soiling.

Instead of disposing the loudspeaker arrange- 55 ment flush with the ground as shown in the

drawing, it is also possible to place such loudspeaker into enclosures or casings having a tortoise-like cover raised but slightly above the ground of the kind serving for traffic regulation in the streets. The loudspeakers could also be 5 set into bases which also are raised but little above the ground. This has the advantage that a listener cannot stand right on top of the speaker.

In the exemplified embodiment of Fig. 1, the 10 loudspeaker is mounted so that its axis presents an inclination to the horizontal. It is, of course, also feasible to mount the loudspeaker so that its axis is parallel to the horizontal as shown in Fig. 2. The reference numerals in Fig. 2 cor- 15 respond to those in Fig. 1. But the arrangement Fig. 2 comprises additional sound duct walls or baffles 7 the effect of which is that the sound radiated off from the loudspeaker 2 issues at an acute angle.

Apart from the modes of mounting of loud- 20 speakers shown in the drawing, recourse could be had also to other forms of mounting. For instance, the loudspeaker axis could present any other angle in reference to the horizontal, pro- 25 vided that care is taken so that the acoustic waves radiated from the loudspeaker are made to issue at an acute angle to the horizontal, and this is done in the embodiment Fig. 2, where the axis is parallel, by the aid of baffles. 30

Another embodiment of this invention is to install a mushroom type loudspeaker, that is, a loudspeaker with non-directional characteristic into the ground as shown in Fig. 3. In the sur- 35 face of the ground, for instance, in the lawn of a parade ground or else in the floor of a room, is an opening 10 adapted to accommodate the non-directional loudspeaker 11. On top the mouth of the loudspeaker is covered by the mushroom-shaped inserted part 12; the outlet 13 for the sound is shut by means of a cover 14 of truncated-cone shape and having sound apertures. The mouth 13 itself is protected against the entrance of water, foreign bodies, etc., 40 by means of a screen 15. The loudspeaker sys- 45 tem is indicated at 16, and the diaphragm at 17. From the loudspeaker 16, a flexible connecting cable 18 is brought to the socket 19 which is preferably mounted fixed in the ground. A drain 50 hole 20 is provided here just as in Figs. 1 and 2.

As regards the arrangement of the drain holes in the embodiments Figs. 1 to 3 it is to be noted that it is recommendable to dispose the loud- 55 speakers a few centimeters above these drain

holes in order that the speaker may not be damaged by possibly occurring clogging of the drains.

What we claim is:

- 5 A subterranean loudspeaker installation comprising a housing disposed underneath the surface of the ground and completely enclosed except for an outlet portion in the upper wall thereof, and a loudspeaker including a diaphragm mounted within the housing so as to subdivide the
- 10 same into two parts, one of which is completely enclosed and the other of which contains the outlet portion, said loudspeaker having its axis parallel to the horizontal, the front of the loudspeaker diaphragm radiating sound waves into

that part having the outlet portion in the upper wall and the back of the diaphragm radiating sound waves into the other part which is completely enclosed, the latter part being lined with felt padding for absorbing the sound waves from the back of the diaphragm, and a plurality of upwardly curved spaced members serving as directional baffle means extending between the front of the diaphragm and the outlet portion of the housing for guiding the sound waves radiated from the front of the diaphragm.
